(57) **CLAIM**

The ornamental design for a pocket camera, as shown and described.

DESCRIPTION

FIG. 1 is a front perspective view of a pocket camera in a closed position showing our new design;

FIG. 2 is a rear perspective view thereof;

FIG. 3 is a front elevational view thereof;

FIG. 4 is a top plan view thereof;

FIG. 5 is a bottom plan view thereof;

FIG. 6 is a rear elevational view thereof;

FIG. 7 is a left side elevational view thereof;

FIG. 8 is a right side elevational view thereof;

FIG. 9 is a front perspective view thereof in an open position; and,

FIG. 10 is a rear perspective view thereof in the open position.

The portions of the camera in broken lines are shown for illustrative purposes only and form no part of the claimed design.

Phantom lining, where utilized, is for illustrative purposes only, and is not intended to limit the claimed component design to the features shown in phantom.
